UNITED STATES PATENT OFFICE.

ROBERT G. McAULEY, OF PITTSBURG, PENNSYLVANIA.

HEATING APPARATUS.

SPECIFICATION forming part of Letters Patent No. 724,918, dated April 7, 1903.

Application filed February 4, 1903. Serial No. 141,827. (No model.)

To all whom it may concern:

Be it known that I, ROBERT G. McAULEY, a citizen of the United States, residing at Pittsburgh, in the county of Allegheny and State of Pennsylvania, have invented certain new and useful Improvements in Heating Apparatus, of which the following is a specification, reference being had therein to the accompanying drawings, forming part of this specification, in which—

Figure 1 is a view in side elevation of a series of my improved heaters assembled, one of the heaters being shown in vertical section. Fig. 2 is a plan view, partially in section, indicated by the line II II of Fig. 1. Fig. 3 is a view in side elevation, showing the hot-air connections from the heaters to distributing-registers. Fig. 4 is a cross-sectional view on the line IV IV of Fig. 1. Fig. 5 is a similar view on the line V V of Fig. 1.

My invention refers to heating apparatus wherein a body of cold air is caused to circulate around and through heating-chambers in contact with heating-surfaces adapted to conduct the products of combustion from a gas or other fuel burner, the heated air being finally conveyed away to any suitable point of distribution.

The objects of the invention are to provide a simple and economical construction for the purpose whereby one or more complete apparatus may be installed, either alone or together, and the heated air produced in such degree and volume as is required for each point of application or distribution—as, for instance, a room as required.

Referring to the drawings, 2 is the base, of cast-iron of any suitable form, but preferably circular, and adapted to contain a gas or fuel burner 3. Upon the top of base 2 is set a pedestal 4, having at its middle portion an upwardly-extending dome 5, providing a cover for the combustion-chamber and having at its upper portion an annular base 6 and outer and inner annular flanges 7 8. The lower portion 4 and upper portion 6 of the pedestal are connected by a series of hollow posts 9, the interior passages 10 of which com-

municate with the combustion-chamber and serve to carry off the products of combustion 50 and to deliver them upwardly between an outer shell 11 and an inner shell 12, of sheet metal. At the upper portion of the apparatus these shells are connected with a top casting 13, provided with an outer annular flange 14 55 and an opening 15 for the products of combustion, with which opening is connected an outlet-flue 16, adapted to carry off the burned gases. The lower base 2 is also provided with a similar annular flange 17, and between 60 said base and top plate 13 is inserted a surrounding outer shell 18, having at any suitable location in its height, but preferably near the top, a series of cold-air-inlet openings 19. As thus assembled all of the various parts of 65 the apparatus are tightly clamped together by two or more vertical bolts 20 passing downwardly through the upper horizontal portion of the casting 13 and the base 4 inside of shell 18. Extending upwardly above the top 13 is 70 the hot-air pipe 21, forming a continuation of the interior 22 within shell 12, by which the heated air is carried off to the registers. Fuel is supplied to the burner 3 by pipe 23, provided with the usual air-mixer and controlling-valve, and the combustion-chamber 75 is provided with a door 24 in the side of the base 2 for lighting or purposes of inspection. If desired, a pilot-burner may be connected with the fuel-pipe and in suitable proximity 80 to the burner 3, so as to ignite the burner, as will be readily understood. As thus constructed cold air enters the space 25, between the casings 11 and 18, through openings 19, passing downwardly and inwardly between 85 and around posts 9 and into contact with dome 5, then upwardly through the interior of the central channel 22, and finally out to conductor-pipe 21. The burner 3 heats the surrounding walls and dome, the products of 90 combustion passing up through conduits 10 in the interior of the posts 9 and into the annular space 26 between the shells 11 and 12, finally passing outwardly through pipe 16 to the flue. In this manner the cold air is 95 brought directly into contact with a large area

of heated partition-surfaces and with the dome and in its downward and upward circulation will become highly heated, according to the degree of heat generated by the 5 burner.

The apparatus is preferably set upon a supporting platform or base 27, located upon suitable pedestals above the floor, and while in the drawings I have shown three of the devices, comprising separate units, as mounted on the same base it will be readily understood that a single unit may be employed or that any number may be mounted and assembled together in the same manner.

15 In Fig. 3 I have indicated in dotted lines an outer surrounding shell or casing 28, adapted to embrace all of the heaters, to the lower portion of which shell air may be supplied from the outside atmosphere by suitable 20 ducting-pipes 29, and by this construction the air will first enter at the base around the heaters and then pass upwardly, becoming partially heated, entering the openings 19, and following the circulation already described.

25 The apparatus may be used as a single unit to supply a single room or so assembled to supply a number of rooms with heated air, and the desired amount and temperature may be easily adjusted in each heater for each 30 separate room. This is a feature of decided advantage and gives economy of fuel, while in their assembled form a number of heaters occupy practically no more space than a single ordinary heater from which various pipe 35 connections are taken for supplying several rooms.

The construction of each unit is very simple and cheap. They may be made in various sizes as required and are so arranged 40 that they may be bolted upon the supporting-base 27 and secured by a bolt at the top by means of flanges 30, as clearly shown in Fig. 1.

The advantages of my invention will be 45 readily appreciated, and while changes and variations may be made in the proportions, arrangement, or other details by the skilled mechanic all such are to be considered as within the scope of the following claims.

50 What I claim is—

1. A heating apparatus consisting of a combustion-chamber, a burner therefor, a covering for the combustion-chamber provided with upwardly-extending combustion-conduits, inner and outer shells providing an extension of said conduits and a central air-passage, and an outer surrounding shell providing an air-space, with means for introducing the air thereto, substantially as set forth.

60 2. A heating apparatus consisting of a combustion-chamber, a burner therefor, a dome-shaped covering for the combustion-chamber provided with upwardly-extending combustion-conduits, inner and outer shells providing an extension of said conduits and a cen-

tral air-passage and an outer surrounding shell providing an air-space, with means for introducing the air thereto, and a hot-air-conducting pipe forming an extension of the central chamber, substantially as set forth.

70 3. A heating apparatus consisting of a combustion-chamber, a burner therefor, a cover for the combustion-chamber provided with a central dome and a series of upwardly-extending combustion-conduits, air-spaces between the conduits, inner and outer shells extending upwardly above the conduits and providing an extension thereof, a central air-passage, an outer surrounding shell providing an air-space, means for introducing the air thereto, and a top, with means for securing the parts together, substantially as set forth.

80 4. A heating apparatus consisting of a combustion-chamber, a burner therefor, a cover for the combustion-chamber provided with a central dome and a series of upwardly-extending combustion-conduits, air-spaces between the conduits, inner and outer shells extending upwardly above the conduits and providing an extension thereof, a central air-passage, an outer surrounding shell providing an air-space, means for introducing the air thereto, and a top, with means for securing the parts together, substantially as set forth.

90 5. A heating apparatus consisting of a hollow base provided with an upwardly-extending flange, a burner located in said base, a 100 covering for the base provided with a dome-shaped central portion, a series of upwardly-extending combustion-conduits with intervening air-spaces, inner and outer flanges and a central opening above said cover, inner and outer shells providing an intervening combustion-conduit and a central air-passage, an outer surrounding shell providing an air-space, a top plate provided with flanges adapted to engage the shells, securing-bolts for 105 clamping the parts together, and a central hot-air-conducting pipe, substantially as set forth.

110 6. A heating apparatus consisting of a hollow base provided with an upwardly-extending flange, a burner located in said base, a covering for the base provided with a dome-shaped central portion, a series of upwardly-extending combustion-conduits with intervening air-spaces, inner and outer flanges and a central opening above said cover; inner and outer shells providing an intervening combustion-conduit and a central air-passage, an outer surrounding shell providing an air-space, a top plate provided with flanges adapted to engage the shells, securing-bolts for 115 clamping the parts together, and a central hot-air-conducting pipe, with means for carrying off the products of combustion substantially as set forth.

7. In a heating apparatus, the combination of a supporting-base, a plurality of heating units consisting of a burner-chamber and burner, upwardly-extending combustion-conduits and outer air-chambers, a top having a securing-flange, a hot-air pipe, a flue-pipe, and a surrounding covering inclosing the heating units and provided with means for admitting air to the interior of the covering and to the air-passages of each unit, substantially as set forth.

In testimony whereof I affix my signature in presence of two witnesses.

ROBERT G. McAULEY.
